RAIL JOINTING MEANS

Harrison Maynard, Earling, W. Va., assignor of
one-half to M. T. Gose, McConnell, W. Va.

Application April 1, 1935, Serial No. 14,156

2 Claims. (Cl. 238—10)

This invention relates to improved rail jointing means which is especially, but not necessarily, adapted for underground track structures used for transportation work in mines and the like.

5 Briefly, the improved jointing means comprises a fish-plate for anchorage on the conventional cross-tie and adapted for disposition on one side of the rail to connect the rail ends together on this side, together with a pair of duplicate companion pivotally mounted units for anchorage on the cross-tie on the opposite side of the track rail in a manner to complete the joint structure.

10 The principal novelty is predicated upon the adoption and use of simple and economical parts especially adapted for the purposes intended and made with a view toward providing a quick and dependable coupling or jointing structure for the abutting rail-ends of the complementary track rails.

20 Other features and advantages will become more readily apparent from the following description and drawings.

In the drawings:

25 Figure 1 is a fragmentary top plan view showing a portion of the cross-tie, the rail sections and the improved coupling or jointing means constructed in accordance with the principles of my invention.

30 Figure 2 is a longitudinal sectional view taken approximately on the plane of the line 2—2 of Figure 1.

Figure 3 is a vertical cross sectional view on the line 3—3 of Figure 2.

35 Figure 4 is a detail view of the one-piece fish-plate used on one side of the rail.

Figure 5 is a perspective of one of the pivoted coupling units used on the opposite side of the rail.

40 Referring now to Figure 1 wherein the general assemblage is shown, it will be observed that the numeral 6 designates the cross-tie. This is a conventional metal tie such as is used in underground track construction work. The rail sections are denoted by the numerals 7 and are shown in abutting relation. On one side is the single cast or one-piece fish-plate. This comprises an attaching or anchoring flange 8 secured by rivets 9 to the cross-tie. It also includes a central inclined web 10 and an upstanding coupling or jointing flange 11. The flange 11 bridges the gap between the rail ends and bears firmly against the apertured web portion of the rail sections 7. It is formed with elongated bolt holes 12 through which the coupling bolts 13 extend.

45 The units on the opposite sides are denoted by

the numerals 14. Each unit comprises a single piece or plate of metal which embodies an arm or lever 15 and at its outer end it is provided with a head or knob 16 which serves as an impact element. Adjacent to the head is an aperture 5 17 to accommodate a pivoting and anchoring bolt or rivet 18. This bolt serves to fasten the lever to the cross-tie and at the same time allows the lever to be swung in a limited arc. The inner end of the lever widens into a plate portion 19 10 and terminates in an upstanding jointing flange 20 which is of the same height as the flange 11 but is approximately one half as long as said flange 11. This abutment flange 20 is provided with a bolt hole 21 to accommodate the adjacent 15 threaded nut equipped end of the connecting bolt 13. There are two of these lever units 14 and they are attached in somewhat spaced parallelism to opposed portions of the cross-tie so that they occupy the complementary positions illustrated in 20 Figure 1. This provides a simple means for swinging the lever units into place after which they may be attached through the instrumentality of the bolts 13. The pivotal mounting of each 25 lever provides a convenient way of enabling the crewmen to use a hammer or the like to strike against the impact head 16 to drive or wedge the flange 20 into place. Under the circumstances this three-part jointing means provides an exceptionally strong, durable and simplified 30 coupling or jointing means for the rail ends 7.

35 The gist of the invention is reflected in a triple part assemblage comprising on the one side a one-piece main fish-plate and on the opposite side and in opposed relation a sectional fish-plate assembly which is in effect a pair of duplicate lever units pivotally mounted and provided with impact heads for the purpose of expeditious application and assembling and maintenance of 40 the parts.

45 It is thought that persons skilled in the art to which the invention relates will be able to obtain a clear understanding of the invention after considering the description in connection with 45 the drawings. Therefore, a more lengthy description is regarded as unnecessary.

50 Minor changes in shape, size and rearrangement of details coming within the field of invention claimed may be resorted to in actual practice, if desired.

Having thus described the invention, what is claimed as new is:

55 1. In a structural assemblage of the class described, in combination, a cross-tie, a sectional

5 rail supported on said cross-tie, the adjacent ends of the sections being disposed in abutting relation in a position overlying the cross-tie, a main fish-plate including an upstanding flange abutting the web portions of the rail sections, an anchoring flange secured to the cross-tie, and a connecting web between said flanges, said web being fashioned to bear against and accommodate the underlying base-flange of the rail sections, a pair of complementary units located on the opposite side of the rail sections and including complementary flanges bearing against the web portions of the rail sections on opposite sides of the joint, said sections including lever portions pivoted on the cross-tie, and bolts passing through the respective flanges of the parts as well as through the web portions of the rail sections

10 to join the parts together rigidly in assembled relationship.

15 2. A rail jointing structure of the class described comprising a main stationary fish-plate unit including an upstanding jointing flange, an anchoring flange and a connecting portion between said flanges, and a pair of companionate jointing units including upstanding flanges for cooperation with said first named upstanding flange, said jointing units being disposed on the opposite sides of the rail from said flange, further including arm portions, and said arm portions having impact heads in the manner and for the purposes described and bolt means for securing the companionate units to the fish plate unit.

HARRISON MAYNARD.
